United States Patent Office.

J. P. DAKE, OF SALEM, OHIO.

Letters Patent No. 80,149, dated July 21, 1868.

IMPROVED APPARATUS FOR EVAPORATING LIQUIDS.

The Schedule referred to in these Letters Patent and making part of the same.

TO ALL WHOM IT MAY CONCERN:

Be it known that I, J. P. DAKE, of Salem, in the county of Columbiana, and State of Ohio, have invented a new and improved Mode of Evaporating Liquids; and I do hereby declare that the following is a full and exact description of the same.

The nature of my invention consists in the application of a close cover, of any desired form and material, fitted upon any evaporating-pan, tank, kettle, or other similar apparatus, so as to admit little no air to the surface of the liquid to be evaporated, except through heated chambers or pipes, arranged around or within the fire-box, and near the door of the furnace, and so as to discharge little or no vapor from the surface of the liquid, except through an opening into an elevated flue or chimney, located at the extreme end of the furnace opposite the door; the object being, by a strong current of dry heated air, to effect a more rapid absorption and removal of vapor from the surface of the liquid.

And I do hereby declare that the following is a full, clear, and exact description of the construction and operation of the same, reference being had to the annexed drawings, making a part of this specification, in which—

Figure 1 is a perspective view of the cover, as placed upon an evaporating-pan, in connection with an air-inlet and an elevated flue or outlet.

A represents the cover, and α a short sections of the same, hinged at b . C represents the chamber or inlet for heated air; B, the furnace, and F the flue or chimney.

Figure 2 is a perspective view of a furnace, with the air-chambers or inlets and the pan, in readiness for the cover.

G represents the pan, C one end of the air-receiving chamber, and E the other.

Figure 3 is a perspective view of a furnace, with the air-receiving chamber in place, and ready for the pan.

D represents the air-chamber, G its outer opening, and E its inner.

Figure 4 is a perspective view of a section of the cover, a little raised, to allow an examination of the contents of the pan, the skimming, the removal or renewal of the same.

A represents the main part of the cover; α , the section or small hinged part. E represents the inner opening of the air-chamber, and C the outer.

Figure 5 is another perspective view of the air-chamber, arranged below and at the sides of the fire-box.

What I claim, therefore, as my invention, and desire to secure by Letters Patent, is—

1. The movable and close-fitting cover A, when used upon the evaporating-pan, tank, or kettle G, in combination with the hot-air chambers C D E, and the elevated flue or chimney F, as set forth and described.

2. The hot-air chambers C D E, when used in combination with the evaporating-pan G, and the close-fitting cover A, in the manner and for the purposes set forth and described.

J. P. DAKE.
